[57] CLAIM

The ornamental design for a golf hole flag pin, as shown and described.

DESCRIPTION

FIG. 1 is an upper right front perspective view of a golf hole flag pin showing my new design;

FIG. 2 is a front elevation view thereof;

FIG. 3 is a right side elevation view thereof;

FIG. 4 is a left side elevation view thereof;

FIG. 5 is a rear elevation view thereof;

FIG. 6 is a top plan view thereof; and,

FIG. 7 is a bottom plan view thereof.

The broken line showing of the putting green (FIG. 1) and bird (FIGS. 1-7) is for illustrative purposes only and forms no part of the claimed design.
